CONTROL DEVICE FOR VACUUM CYLINDERS

Howard E. Ricketson, United States Army

Application October 25, 1945, Serial No. 624,633

5 Claims. (Cl. 121—38)

(Granted under the act of March 3, 1883, as
amended April 30, 1928; 370 O. G. 757)

1

The invention described herein may be manufactured and used by or for the Government for governmental purposes, without payment to me of any royalty thereon.

This invention relates to vacuum cylinders and more particularly to control devices therefor. Such cylinders are utilized for many purposes; and either the piston or the cylinder itself may move under the influence of the vacuum while the other element remains stationary.

Generally stated, it is old in the art to employ vacuum cylinders with control devices for adjusting its speed of operation, but such devices are usually designed to effect an adjustment which does not vary throughout the stroke of the movable element.

I have found that in numerous installations greatly improved results may be obtained by arranging for the movable element to travel at progressively slower speeds along the length of its stroke. More specifically, this will result in the cushioning of undesirable shock without appreciable retardation of the operating cycle.

In vacuum-controlled excavating machines of the shovel-and-crane type, for example, considerable difficulty is presented for the reason that because of the necessity of having to exhaust the air from the line and from the vacuum cylinder before the clutch will engage there develops a time lag between the instant that the operator opens the control valve and the moment the clutch actually engages; and during this time lag, the operator opens the control valve too wide. This excessive opening of the control valve causes the ultimate sharp engagement of the clutch with a resultant jerky and violent operation accompanied by injurious shock to the machine.

Certain expedients (such as the use of a restrictor at a suitable point in the vacuum line) result in smoothing out the engagement of the clutch; but the use thereof slows down the operation of the vacuum cylinder and increases the time lag both on engagement and also on the release of the clutch. This is objectionable from an operational point of view.

It is among the objects of the present invention to provide a control device for vacuum cylinders which will result in an even action without increase in time lag.

Another object is to so control the air input of a device of the class described as to cause progressively decreasing speed in the operating stroke to thereby prevent injury from suddenly imposed strains, and at the same time, provide for a rapid output or exhaust on the return movement.

Another object is the provision of a vacuum cylinder wherein the admission of air under atmospheric pressure is metered, together with means for effecting the rapid exhaust referred to.

2

With such construction and arrangement, the operator of the machine (for example, the shovel-and-crane previously mentioned) may move the control valve wide open, but the clutch will engage smoothly and only as fast as the metering effect will permit; while the rapid exhaust means enables instantaneous release.

Still another object is to provide a device of the class described which is cheap and easy to manufacture and durable in service.

The invention, then, comprises the features hereinafter fully described, and as particularly pointed out in the claims, the following description and the annexed drawings setting forth in detail certain illustrative embodiments of the invention, these being indicative of but several of numerous ways in which the principles of the invention may be employed.

In said drawings:

20 Figure 1 is a longitudinal view, mostly in section, illustrating the association of the operating instrumentalities of the device of the invention with the vacuum cylinder and the pistons disposed therein;

25 Figure 2 is a view similar to that of Fig. 1, but discloses a permissive modification; and

Figure 3 is a sectional view on the line 3—3 of Fig. 2.

Referring more particularly to the drawings the 30 numeral 2 designates a vacuum line from a suitable source of low pressure, the said line being connected, to a vacuum cylinder 3. In the manner well known in the art, the vacuum cylinder 3 is provided with a connector 4 by which the 35 said cylinder is connected to the element which it is intended to operate, for example, the operating lever of a mechanical clutch (not shown). Within the vacuum cylinder 3 is a piston 5 to which there is connected a piston rod 6, the latter 40 projecting from the said cylinder as shown. This piston rod 6 may, if desired, be conveniently anchored and thus rendered immobile.

The vacuum cylinder 3 and its interiorly disposed piston 5 are of more or less conventional 45 design. However, the piston rod 6 is of modified design as will appear. This piston rod 6 is provided with a central passage 9 which is closed at its ends. The inner end of the central passage 9 50 communicates with a right angularly extending port 10 which in turn communicates with the inside of the vacuum cylinder 3 at a point immediately adjacent the proximate face of the piston 5. At appropriate points along its length, the piston rod 6 is provided with air inlet ports, as shown at 55 12, 13 and 14, the latter being disposed adjacent the outer end of the said piston rod.

Both ends of the vacuum cylinder 3 are closed 60 as shown at 16 and 17, and the closure 17 from which the piston rod 6 projects is provided with a centrally disposed sleeve 18 which serves as a

bearing. The outer end of this centrally disposed sleeve 18 projects from the closure 17 and carries an annularly rotatable collar 20 which is secured against rotation and/or longitudinal movement by a set screw 21. As shown in Figure 1 the annular collar 20 closely embraces the piston rod 6 and is provided with a peripheral recess which is defined by a longitudinally extending wall 22 and a flat angular wall 23 which extends inwardly and converges upon the longitudinally extending wall 22. Thus, the walls 22 and 23 of the collar 20 define a right-angled triangle, the apex of which lies inwardly of the outer end of the said collar.

Accordingly, to the foregoing construction and arrangement, the atmospheric air entering the vacuum cylinder 3 is metered through the air inlet ports 12, 13 and 14 in the piston rod 6. The hole 14 is always exposed, but extent of exposure of the holes 12 and 13 is regulated by the adjustment of the rotational position of the triangular recess in the annular collar 20. Thus, when all three holes (i. e. 12, 13 and 14) are exposed, the vacuum inlet end of the vacuum cylinder 3 is drawn toward the piston rod 6 at a rate which is initially very rapid and decreasingly slower as the exposure of the holes 12 and 13 is foreclosed. This metering effect accomplishes the results referred to hereinbefore.

In order to assure the quick return of the vacuum cylinder 3 to its initial position, the closure 17 which is on the "atmospheric air" side of the piston 5, is provided with a quick-operating disk-type of exhaust valve 25 which, upon being operated by the air pressure in the "atmospheric air" pressure side of the piston, releases the air and permits the cylinder to drop to its initial position under gravity, that is, by its own weight.

In Figure 2 of the drawings there is shown a modified form of metering device, the same comprising a slot 26 which extends from the inner end of the piston rod 6 to a point adjacent the outer end thereof. This slot 26 is a dove-tail contour, being defined by a flat bottom 27, and a pair of outwardly convergent flat side walls 28. Within the dovetail slot 26 there is disposed a slidable wedge 30, the bottom and side walls of which conform to the size and shape of the corresponding portions of the said slot, as shown in Figure 3 of the drawings. The wedge formation of the slidable wedge 30 accrues from the tapering of its outer surface inwardly toward the piston 5. A bushing 32 or other suitable sealing means may be disposed within the sleeve 18 as shown. Whether using either the embodiment of Figure 1, or the permissive modification of Figure 2, the intake of air at atmospheric pressure into the vacuum cylinder 3 is metered to provide for rapid initial movement followed by progressive decrease as the vacuum cylinder 3 moves toward the piston 5.

Having thus described my invention, what I claim as new and wish to secure by Letters Patents is:

1. A vacuum cylinder assembly comprising a vacuum cylinder provided with a closure at both ends, a piston disposed within said cylinder, means for connecting one end of said cylinder with a source of vacuum, a piston rod extending through the other end of said cylinder and connected to said piston, a check valve permitting a rapid exhaust flow from the cylinder to the atmosphere, said check valve carried by the last-named end of said cylinder, and means for metering atmospheric air through said piston rod.

5 2. A vacuum cylinder assembly comprising a vacuum cylinder provided with a closure at both ends, a piston disposed within said cylinder, means for connecting one end of said cylinder with a source of vacuum, a piston rod extending through the closure at the other end of said cylinder and connected to said piston, a check valve permitting a rapid exhaust flow from the cylinder to the atmosphere carried by the last-named end of said cylinder, said piston rod having a central passage communicating with the adjacent side of said piston and spaced air inlet openings communicating with the atmosphere, and means for closing at least one of said spaced air inlet openings during the operating stroke of said vacuum cylinder.

10 3. A vacuum cylinder assembly comprising a vacuum cylinder provided with a closure at both ends, a piston disposed within said cylinder, means for connecting one end of said cylinder with a source of vacuum, a piston rod extending through the closure at the other end of said cylinder and connected to said piston, a check valve permitting a rapid exhaust flow from the cylinder to the atmosphere carried by the last-named end of said cylinder, said piston rod having a central passage communicating with the adjacent side of said piston and spaced air inlet openings communicating with the atmosphere, means for closing at least one of said spaced air inlet openings during the operating stroke of said vacuum cylinder, said last-named means comprising an adjustable sleeve on the exterior of said cylinder, and means for adjustably positioning said sleeve 15 to regulate the extent of operation of at least one of said spaced air inlet openings.

20 4. A vacuum cylinder assembly comprising a vacuum cylinder provided with a closure at both ends, a piston disposed within said cylinder, means for connecting one end of said cylinder with a source of vacuum, a piston rod extending through the closure at the other end of said cylinder and connected to said piston, a check valve permitting a rapid exhaust flow from the cylinder to the atmosphere carried by the last-named end of said cylinder, said piston rod having a longitudinal slot, and a wedge disposed in said slot, said wedge being longitudinally adjustable to vary the size of the opening between said slot 25 and the adjacent cylinder closure at any given position in the operating stroke of said vacuum cylinder.

25 5. A vacuum cylinder assembly comprising a stationary piston, a closed cylinder reciprocably mounted on said piston, a piston rod connected to said piston and extending exteriorly of said cylinder, means for connecting one end of said cylinder to a source of vacuum whereby one side of said piston is in contact with said vacuum, a check valve mounted on the other end of said cylinder, said check valve permitting a rapid exhaust flow from the cylinder to the atmosphere, and a means for metering atmospheric air to the last mentioned end of said cylinder whereby air 30 may be applied to the other side of said piston.
